UNITED STATES PATENT OFFICE.

AUGUST L. SIEGHORTNER, OF ASBURY PARK, NEW JERSEY, ASSIGNOR TO
BERRANG & ZACHARIAS, OF SAME PLACE.

DESIGN FOR A CAP FOR COLLAPSIBLE TUBES.

SPECIFICATION forming part of Design No. 28,854, dated June 14, 1898.

Application filed September 30, 1897. Serial No. 653,651. Term of patent 7 years.

To all whom it may concern:

Be it known that I, AUGUST L. SIEGHORTNER, a citizen of the United States, residing at Asbury Park, in the county of Monmouth and State of New Jersey, have invented and produced a new and original Design for a Cap for Collapsible Tubes; and I do hereby declare the following to be a full, clear, and exact description of the same, reference being had to the accompanying drawings, forming a part thereof.

My invention relates to the unitary design for an ornamental cap for collapsible tubes, as shown in the accompanying drawings, in which—

Figure 1 is a perspective view of a cap embodying my new design, and Fig. 2 is a vertical longitudinal section of the same.

A in the drawings designates the tubular body portion of the cap, which is formed at its lower end with a cylindrical base collar or sleeve B and at its upper end with a cylindrical head C. The said lower end of the body portion is flared outwardly, as at d, and corresponds substantially in contour to the

mouth of a bell, and from this point it gradually assumes an inwardly-reducing conical shape to its upper end, where it is joined to the lower end of the head by a neck e, which is indented to form an exterior circumferential groove f.

The head C is approximately of the same diameter as the upper extremity of the body portion A and of correspondingly smaller diameter than the base collar or sleeve B.

The crown g of the head is semiglobular in form, and the lower edge h of the base-collar is flared outward slightly to form an annular lip or bead projection, as shown.

Having thus described my invention, what I claim is—

The design for a cap for collapsible tubes, as herein shown and described.

In testimony whereof I affix my signature in presence of two witnesses.

AUGUST L. SIEGHORTNER.
